UNITED STATES PATENT OFFICE.

GEORGE F. HAMMOND, OF CLEVELAND, OHIO.

DEVICE FOR PRESSING CLOTHES.

1,192,518.

Specification of Letters Patent. Patented July 25, 1916.

Application filed September 6, 1912. Serial No. 718,847.

To all whom it may concern:

Be it known that I, GEORGE F. HAMMOND, a citizen of the United States, residing at Cleveland, in the county of Cuyahoga and 5 State of Ohio, have invented a certain new and useful Improvement in Devices for Pressing Clothes, of which the following is a full, clear, and exact description, reference being had to the accompanying drawings.

10 This invention relates to devices for pressing clothes and particularly to such devices as can be employed without the necessity of removing the clothes from the body.

15 The objects of the invention are the provision of a device of this character of light weight and easy manipulation by which portions of garments, such as bottoms of skirts, trousers legs and coat sleeves may be creased, 20 coat lapels straightened and smoothed, pocket flaps flattened, and other minor improvements effected in an expeditious manner, and without the necessity of removing the clothes from the wearer's body; the provision of a device of this character of great 25 simplicity, reliability, and freedom from derangement; while further objects and advantages of the invention will become apparent as the description proceeds.

30 It is conceived that the device will find its widest use in barber shops and bootblack stands for creasing the trousers of patrons in the chairs and for improving the appearance of the more prominent parts of their 35 coats, although it will be understood that the same is not restricted to this use, and that it can be applied to portions of ladies' and children's clothing with equally desirable results.

40 Generally speaking my invention may be defined as consisting of the constructions and combinations defined in the claims here-to annexed and illustrated in the drawings accompanying and forming part hereof, 45 wherein:

Figure 1 is a plan view of a device constructed in accordance with my invention; Fig. 2 is a side elevational view of the same; Fig. 3 is a cross sectional view upon the 50 line 3—3 of Fig. 2; Fig. 4 represents the manner of using the device; Fig. 5 is a diagrammatic view illustrating the wiring connections; and Fig. 6 is a plan view of a modified form of the device. Fig. 7 is a 55 detail in side view of a modification.

Describing specifically the construction

illustrated in Figs. 1 to 5 inclusive, the pressing device proper is illustrated as consisting of a U-shaped metallic frame having forwardly extending, spaced side portions 60 or arms 1—1 connected by an integral base portion 2, the same being formed of strap metal of greater width than thickness and possessing a certain amount of resilience. Secured to the portion 2 is a handle 3 whereby the device may be grasped. The opposite end of each of the arms or sides 1—1 is formed with a pair of vertically-spaced, forwardly-projecting branches 4—4 forming a bracket, the ends whereof are rolled 65 to form loops 4^a—4^a. These branches are preferably formed in the same plane with their respective sides but project forwardly at an oblique angle therewith as illustrated in Figs. 2 and 4. The loops 4^a—4^a of the 70 same pair of branches are formed in alignment with each other so as to receive the ends 5—5 of a spindle 6. This spindle is made of insulating material such as fiber and carries electrical heating elements represented generally at 7 intermediate of its ends. The terminals of the resistance coils are connected to pole pieces 8—8 located in the ends of the spindles, which pole pieces are secured to the binding screws 9—9. Ro- 75 tatably journaled upon each of these spindles is a hollow cylindrical metallic drum 10, whose interior size is sufficiently great to prevent contact with the heating elements 80 7 and whose length is such as substantially 90 to fill the space between the opposite branches of each pair of brackets. In the construction illustrated herein, one end of the drum is closed by an integral web 11 having a central aperture surrounded by an 95 inturned flange 12 forming an extended bearing on the surface of the spindle. The other end is closed by a removable plate 13, likewise having a central aperture surrounded by a flange. The distance between 100 the opposite sides 1—1 of the frame is such as to cause the elasticity of the same to press the two drums against each other with the force requisite to the proper treatment of the clothing.

In the construction herein shown the main wires 16 and 17 are led in through the end of the handle by means of a flexible conduit 18, after which they are divided, one branch going to one end of each of the spindles as shown at 16^a and 17^a (Fig. 5), and the opposite ends of the spindles being con- 105 110

nected together through a connection 19. The portions of these wires within the frame are preferably inclosed in suitable channels 20 secured to the inner faces of the sides 1—1. This method of wiring distributes the potential equally within the two drums, as will be obvious, although other arrangements could be employed within the scope of my invention.

10 For the purpose of separating the drums so as to facilitate their application to the clothing I may employ the construction shown in Figs. 1, 2, and 3, wherein I have illustrated bracket members 25 secured to the inner faces of the sides 1—1 and straddling the channels 20, suitable links 26 being pivoted to each of these brackets, and the free ends of the links being pivoted together so as to form a toggle joint. One of these links may be provided with a handle 27 whereby the same may be straightened to spread the sides apart. I have shown one of these links as provided with a laterally extending lip 28 adapted to engage the other link when the toggle is straightened so as to prevent the same from moving more than a limited distance past the line of centers, whereby the drums will be maintained in spaced position for as long a time as desired.

30 It will be obvious that with this device a gentleman's trousers can be easily creased while he is reclining in a barber's chair as indicated in Fig. 4, one hand of the operator being sufficient to manipulate the pressing device, while the other hand is free to support and straighten the cloth adjacent to the crease. The rotatable nature of the drums permits them to be rolled along the cloth at the rate necessary to crease the same without burning, while the rolling contact prevents the glossing of the cloth as would be the case if a sliding contact were used.

40 45 In case a flat contact of greater area be desired without the rolling effect obtained by the construction above described, the device shown in Fig. 6 may be employed. In this embodiment the arms or sides 1^a—1^a of 50 the frame are extended to form handles 30—30, the sides of the handles at their forward ends being folded inwardly as illustrated at 31 to overlap each other and pivoted together upon an axis transverse there- 55 to. In the construction shown herein, one of the pivots consists of a hollow rivet or eyelet 32 through which the flexible cord 18 is inserted. Secured to the inner faces of the other ends of the members 1^a—1^a are 60 the hollow rectangular metallic blocks 33, 33 within which suitable heating elements indicated generally at 34, 34 are located. These blocks may be several inches in length, the parts being foreshortened in the drawing. Suitable resilient means, such as the

70 spring 35, may be employed for forcing the adjacent faces of these blocks toward each other into contact with the layers of cloth introduced therebetween. With this construction it is expected that the blocks 33 75 will be clamped for a time upon one portion of the goods until the same has been properly treated, whereupon they will be shifted to a succeeding portion of the goods. It is considered preferable with this construction to have the pressure applied by a 80 spring rather than by hand, partly because of the greater uniformity thereby secured and partly because of the smaller amount of muscular effort necessitated. It is obvious, however, that a reversal could be employed without invention.

85 In Fig. 7 of the drawing there is shown a modification of the drum 10^a over that shown in Figs. 1 and 3 to 5 inclusive. The drums 10^a of Fig. 7 are provided with longitudinally extending projections 36 adapted to coöperate with complementary recesses 37, the projections of one drum being adapted to coöperate with the recesses of the other. This form of drum is particularly applicable for fluting ladies' garments.

90 95 It is obvious that the method of mounting and connecting the electrical elements could be varied widely without departing from the scope of my invention. It will also be clear that a great many changes in details and constructions of parts may be adopted within the limits of my inventive idea.

100 While I have necessarily described my invention in detail, I do not propose to be limited to such details, except as the same may be specifically included in the claims hereto annexed.

Having thus described my invention, I 105 claim:

1. The combination of a frame having opposite branches, opposite ironing drums carried by said branches, the frame being elastic and shaped to normally press said drums together by its own elasticity, and means for springing the frame to separate said drums.

2. In a device of the character described, the combination, with a U-shaped frame of resilient material having forwardly extending spaced arms, of ironing drums secured to the forward end of each of said arms, the resilience of the frame being such as normally to draw said drums toward each other, a handle secured to a portion of said frame removed from said drums, and means for spreading apart the arms of said frame so as to separate said drums.

3. In a device of the character described, the combination with a U-shaped frame of resilient material having forwardly extending spaced arms, of an ironing drum secured to the forward end of each of said arms, the resilience of the frame being such

as normally to draw said drums together, a handle secured to a portion of said frame removed from said drums, and a pair of links having their inner ends pivoted together and having their outer ends pivoted to the arms of said frame so as to form a toggle joint, whereby said arms can be spread apart and said drums separated.

4. In a device of the character described, the combination, with a frame having a pair of forwardly extending spaced arms, each of said arms being formed at its forward end with a pair of spaced, forwardly extending brackets substantially in the plane thereof, of an ironing drum mounted between each of said brackets and adapted to engage the drum carried by the brackets of the opposite arms, a handle secured to a portion of said frame removed from said drums, means for drawing said drums toward each other so as to press upon articles introduced therebetween, and means for separating said

drums forcibly from each other so as to permit the introduction of such articles therebetween.

5. In a device of the character described, the combination, with a U-shaped frame having spaced, forwardly extending arms, of cylindrical ironing drums rotatably journaled at the ends of said arms with their axes substantially in the plane of said arms, a handle secured to the end of the frame remote from said drums and central with respect to the frame, and means for varying the distance between said arms so as to move said drums toward and from each other.

In testimony whereof, I hereunto affix my signature in the presence of two witnesses.

GEORGE F. HAMMOND.
